UNITED STATES PATENT OFFICE

1,929,394

PRINTED REGENERATED CELLULOSE AND
A METHOD OF PRODUCING IT

Julius Voss, Wiesbaden-Biebrich, Germany, assignor to The Visking Corporation, Chicago, Ill., a corporation of Virginia

Application March 31, 1933, Serial No. 663,822,
and in Germany November 12, 1931

8 Claims. (Cl. 101—426)

The invention relates to the art of printing on regenerated cellulose and has as its primary object the production of articles formed from regenerated cellulose and printed with ink or colors which will not be injured or detached from the regenerated cellulose when the articles are subjected to cooking and smoking processes.

An illustrative embodiment of the product of the invention and of apparatus for carrying out the process thereof is shown in the accompanying drawing, in which:

Fig. 1 is a perspective view of a tubular article, as a sausage casing, marked in accordance with the invention, and

Fig. 2 is a vertical section of a vacuumized heating chamber for treatment of the material.

The invention is particularly adapted to be employed in the printing of data on sausage casings which are formed from regenerated cellulose but the invention is limited to this use only to the extent indicated in the appended claims.

It is known that one may print on sheets of regenerated cellulose with inks, colors or paints having an oil base. These inks, colors or paints adhere to the regenerated cellulose under normal conditions and are not readily washed therefrom. Heretofore, however, if the printed regenerated cellulose were placed in hot water, the printed data was loosened from the regenerated cellulose. Therefore, the use of inks, colors or paints of the character described on sausage casings of regenerated cellulose was of no particular advantage as the sausages were usually subjected to cooking and smoking operations. In the smoking operation, the inks, colors or paints had a tendency to become discolored. Therefore, it has been impossible heretofore to produce satisfactory imprints on sausage casings formed from regenerated cellulose as the imprints would be injured or destroyed during the cooking and smoking processes.

I have now learned that the inks, colors or paints of the character described, may be treated so that they will not be injured or discolored to any appreciable extent by the cooking and smoking operations. Thus, when the inks, colors or paints of the character described are employed in the printing of data on articles formed of regenerated cellulose, they will resist the deteriorating effects of the smoking and drying operations if, after a surface drying of the printed data has been effected, they are subjected for a short time to a relatively high temperature, it being preferable that the air be

maintained relatively moist or humid so that the surface of the regenerated cellulose does not become too dry or brittle. For example, the imprints, a short time after the printing operation, may be subjected for about one hour to a temperature of approximately 100° C. The imprints will then acquire such characteristics that they will withstand the cooking and smoking operations with no injury to them. In another form of the invention, the printed regenerated cellulose is stored or seasoned for about fourteen days and then subjected for about one hour to a temperature of approximately 60° C. in a partial vacuum. The imprints will then become resistant to the deteriorating tendencies of the smoking and cooking operations.

All inks or colors in which the vehicle for the pigment comprises quick-drying oxidizing oils are particularly adapted for producing imprints embodying the invention.

In the drawing there is shown a tubular article, as a sausage casing, of regenerated cellulose having lettering as 14 formed thereon in any desired manner, utilizing an oxidizing oil bearing a pigment. At 11 is shown a chamber or oven which may be tightly closed and the air therein rarefied as by a pump, not shown, connected to suction pipe 13. To heat the chamber 11, there is shown a coil 12 in which a heating medium as steam may be circulated whereby the temperature of the air in the chamber 12 may be raised to approximately 100° C.

While I have shown and described certain embodiments of my invention, it is to be understood that it is capable of many modifications. Changes, therefore in the construction and arrangement may be made without departing from the spirit and scope of the invention as disclosed in the appended claims, in which it is my intention to claim all novelty inherent in my invention as broadly as possible, in view of the prior art.

I claim:

1. A process for producing imprints on articles of regenerated cellulose, which process comprises drying the surfaces of the imprints, and then subjecting them to a high temperature in a relatively humid atmosphere.

2. A process for producing imprints on articles of regenerated cellulose, which process comprises forming said imprints from colors having an oil base, and then subjecting the printed matter to a higher temperature in a relatively humid atmosphere after the printing operation.

3. A process for producing imprints on articles of regenerated cellulose, which process comprises

- printing on said cellulose with a color having an oil base, then permitting the surface of the printed matter to dry, and then subjecting the printed matter to a high temperature. 5. A process of producing imprints on articles of regenerated cellulose, which process comprises subjecting the imprinted material to a temperature of approximately 100° C. in a relatively humid atmosphere after the printing operation. 10. A process for producing substantially permanent imprints on articles of regenerated cellulose, which process includes the step of heating the printed material to a high temperature in partial vacuum. 15. A process for producing substantially permanent imprints on articles of regenerated cellulose, which process includes the step of heating the printed material to a high temperature after the printing operation in a partial vacuum. 7. A process for producing imprints on articles of regenerated cellulose, which process comprises seasoning said printed articles for approximately fourteen days after the printing operation, and then subjecting them to a higher temperature than the temperature to which they are subjected while being seasoned. 8. An article formed from regenerated cellulose and having data printed thereon with a color having an oil base resistant to boiling.
